DISPLAY RACK

George H. Jantzen, New York, N.Y., assignor to Steinthal Sample Co., Inc., New York, N.Y., a corporation of New York

Filed Jan. 8, 1962, Ser. No. 164,724

6 Claims. (Cl. 211—47)

The present invention relates to a display rack and relates, more particularly, to a rack for displaying a number of sample swatches of fabric or the like.

An object of the invention is to provide a rack for displaying a number of sample swatches in a manner in which each of the swatches may be readily inspected. A further object of the invention is to provide a display rack which permits the sample swatches to be installed on the rack or to be removed therefrom without the use of tools.

Other objects and advantages of the invention will become apparent and will be better understood from the following description and the accompanying drawings, in which:

FIG. 1 is a front elevational view of a display rack embodying the invention;

FIG. 2 is a perspective view on an enlarged scale of the display rack shown in FIG. 1 with certain parts thereof being shown in exploded relation;

FIG. 3 is a fragmentary view in vertical section and on an enlarged scale of a part of the display rack shown in FIG. 1;

FIG. 4 is a fragmentary view in partial section of a portion of the display rack shown in FIG. 1, but on a still larger scale; and

FIG. 5 is a section view taken along the line 5—5 of FIG. 3.

Referring to the drawings in detail, a display rack embodying the invention comprises an upright support 10 which may be in the form of a rod. The lower end of the support fits into a socket 11 mounted on top of a base 12 which holds the support in a vertical position.

The upper end of the vertical support is connected by suitable means to the center of a horizontal cross-bar 13 which forms arms 13a extending outwardly from the vertical support on opposite sides thereof. The arms carry swatch supporting structures which are identical and hence, only one need be described.

Each arm which may be of rectangular cross-section with a round shaft-like portion 13b at its outer end, carries a pair of spaced end plates 14, 15 in the form of discs which may be made from plastic or other suitable material. One of the end plates is located on the arm adjacent the center support, and a pair of sleeves 16 having annular flanges 17 are mounted on the arm so that the flanges bear against opposite sides of the plate. In addition, a tubular member 18 surrounds the arm and extends between the two end plates.

The end of one of the sleeves extends into the tubular member and engages with one end of a coil spring 19 located inside of the tubular member. The other end of the coil spring abuts against a C-washer 20 which fits into a circular groove 21 in the arm and the sleeve can be moved into the tubular member against the pressure of the spring. Thus, the spring normally urges the sample-supporting plate toward the center support through its action on the sleeve, but as shown in FIG. 4, the plate may be moved inwardly by finger pressure against the force of the spring.

The other end plate is carried at the round shaft-like end of the arm. A sleeve 22 having an annular flange 23 is carried by the arm with the flange bearing against the inner surface of the plate and with the other end

2

of the sleeve extending into the tubular member on the arm. A self-holding type of washer 24 which is forced onto the end of the arm on the outside of the plate, holds the plate and the entire assembly in place on the arm. The end of the arm may be capped by a ball 25.

The outer surface of each of the end plates contains a groove 26 which extends around the plate adjacent its outer perimeter and is shaped to receive a hook-shaped end 27 of a wire rod 28 to which a sample swatch 29 is attached. The hook-shaped ends of the wire rod face inwardly or toward each other and are spaced so that when the end plates are at their normal spacing, they will extend into grooves in the outer surfaces of the respective plates. Under these conditions, the coil spring 15 maintains the end plates at their normal spacing and the plates in turn support the swatches.

As shown in FIG. 4, a sample swatch may be readily removed from the display unit by pushing the inner end plate along the arm against the action of the spring so as to reduce the distance between the end plates by an amount sufficient to permit the hooked end of the wire rod to be released from the grooves in the outer surfaces of the plates. The same procedure is followed in adding swatches to the display rack and both operations can be readily accomplished without the use of tools.

The swatches are attached to the wire rod by means of a paper backing 30 or the like which is folded around the rod and has its free ends attached to the sample. Identification of the sample may be printed on the backing.

A large number of sample swatches may be displayed on a rack constructed in this manner and the individual swatches can be freely moved around the end plates from which they are supported.

It will be understood that various changes and modifications may be made in the particular embodiment of the invention which has been illustrated and described herein without departing from the spirit or scope of the invention as defined by the following claims.

What is claimed is:

1. A display rack for exhibiting sample swatches, which comprises an upright support, an arm connected to and extending outwardly from said support, a pair of end plates carried on said arm, each of said end plates having an outer surface which contains a groove extending around the plate adjacent its outer edge and at least one of said plates being slidable on the arm for maintaining said plates in spaced relation relative to each other, and a swatch supporting member extending between the spaced plates at the outer edges thereof, said swatch supporting member having portions at opposite ends thereof which fit into the grooves in the outer surfaces of the end plates.

2. A display rack for exhibiting sample swatches, which comprises an upright support, a pair of arms connected to and extending outwardly from said support, a pair of end plates carried by each of said arms, each of said end plates having an outer surface which contains a groove extending around the plate adjacent its outer edge, one of the plates of each pair being slidable on the arm, spring means for maintaining the plates of each pair in spaced relation relative to each other, and swatch supporting members extending between the plates of each pair at their outer edges, each of said members having portions at their ends fitting into the grooves in outer surfaces of the end plates.

3. In a rack for displaying sample swatches, the combination which includes an arm, a pair of end plates carried by said arm, each of said end plates having an outer surface which contains a groove extending around

the plate adjacent its outer edge, at least one of said plates being slidable on the arm, spring means for resiliently maintaining said plates in predetermined spaced relation relative to each other, and a sample swatch supporting member extending between the spaced plates at the outer edges thereof, said member having portions at its ends extending into the grooves in the outer surfaces of the end plates.

4. In a rack for displaying a number of sample swatches, the combination which includes an arm, a pair of end plates carried by said arm at opposite ends thereof, at least one of said plates being slidable lengthwise of the arm, each of said end plates having an outer surface which contains a groove extending around the plate adjacent its outer edge, a tubular member surrounding the arm and extending between the end plates, a coil spring located inside of the tubular member and acting on the slidable end plate, said spring resiliently urging said slidable end plate toward a predetermined position with respect to the other end plate, and a member for supporting a sample swatch extending the plates at their outer edges, said member having inwardly-facing, hook-shaped portions at its ends extending into the grooves in the outer surfaces of the end plates.

5. A rack for displaying a series of sample swatches, which comprises a supporting arm, a pair of plates mounted on said arm, at least one of the plates being movable lengthwise of the arm relative to the other plate, spring means acting on and normally urging the movable plate toward a position spaced from the other plate, each of said plates having an outwardly facing surface, each of said outwardly facing surfaces having a groove formed

5

therein and extending around the plate adjacent an outer edge thereof, a swatch supporting member extending between the end plates, said swatch supporting member having inwardly facing hook shaped portions at opposite ends thereof, each of said hook shaped portions having an end extending into the groove in the outwardly facing surface of one of the plates and being removable therefrom upon movement of the movable plate toward the other plate.

10

6. A rack for displaying a series of sample swatches, which comprises a supporting arm, a pair of plates mounted on said arm in spaced relation to each other, at least one of said plates being movable relative to the other plate, each of said plates having a surface extending outwardly from the supporting arm, each of said surfaces having a groove formed therein and extending around the plate adjacent an outer edge thereof, a swatch supporting member extending between said plates, said swatch supporting member having opposite ends extending into the grooves in the respective plates, and spring means acting on the movable plate and normally urging said plate toward a position where the ends of the swatch supporting member are located within the grooves in the surfaces of the plates.
